ATTORNEY

UNITED STATES PATENT OFFICE.

BENJAMIN E. GETCHELL, OF PLAINVILLE, CONNECTICUT, ASSIGNOR TO THE TRUE-BULL ELECTRIC MANUFACTURING COMPANY, OF PLAINVILLE, CONNECTICUT, A CORPORATION OF CONNECTICUT.

ELECTRIC SWITCH.

Application filed September 8, 1923. Serial No. 337,651.

To all whom it may concern:

Be it known that I, BENJAMIN E. GETCHELL, a citizen of the United States of America, residing at Plainville, Connecticut, have invented a new and useful Electric Switch, of which the following is a specification.

My invention relates particularly to the movable contacts of an electric switch and 10 the method of mounting and operating the same.

The main object is to provide a construction which can be made economically and readily operated, and in which the movable 15 contacts are so supported as to insure an even engagement with the stationary contacts.

Another object is to construct the parts so 20 that the contact members may be readily assembled or separated from the contact carrier.

Another object is to provide a construction 25 in which the contacts are somewhat loosely mounted so as to allow for irregularities in construction and assembly.

Figure 1 is a front view of a switch embodying improvements of my invention, the parts being shown in the open circuit position.

30 Fig. 2 is a side view of the same.

Fig. 3 is a perspective view of the movable contacts and carrier.

Fig. 4 is a perspective view of one of the 35 movable contacts.

Fig. 5 is a sectional view of the carrier showing one of the contacts.

Fig. 6 is a plan view of a fragment of the carrier with a contact in place.

In the particular form shown, the insulating base 10 supports two pairs of spring jaw contacts 11 and 12 having contact faces elevated from the base and spaced apart from each other.

The movable contacts 13 are in the form 45 of blades loosely carried by the cylinders 14 in line with the jaws of the respective contacts 11 and 12.

The cylinder 14 is provided with hubs 15 mounted to oscillate in the brackets 16 at 50 opposite sides of the base.

The contact cylinder 14 is preferably provided with a projecting member 17 adapted to oscillate in a slot 18. The cylinder and

movable contacts may be operated in any suitable manner, for instance, through the medium of the projection 17 or otherwise. The particular construction herein shown is intended to be operated by quick-break mechanism in a box or receptacle of the safety type, but the invention herein claimed is not limited to such a construction. I prefer to provide a spring pressed plunger 19 adapted to fit in a cup-like recess or socket 20 in one of the brackets 16 to yieldingly hold the movable cylinder 14 in position.

As above mentioned, the blades 13 are preferably loosely mounted in the cylinder 14 so that they are free to adjust themselves laterally and angularly to contact closely with the spring jaws. This may conveniently be accomplished by having the passage 21 in the cylinder somewhat larger than the blade itself so that the blade can readily be inserted through the cylinder and then secured in position. For holding 75 the blade in place I may provide a lug 22 struck up from the body of the blade and adapted to project beyond the edge of the recess 21. A cotter-pin 23 is adapted to be inserted through the opposite end of the blade. This effectively holds the blade in place endwise but leaves it loose laterally so that it readily adjusts itself to slight irregularity in the location of the parts. This forms a very cheap but effective and as satisfactory construction in which the contact blades are effectively insulated from each other and from the other parts of the mechanism when in the open circuit position.

It is obvious that two lugs like 22 may be used to secure the blades in position in which case one of the lugs would be bent over after the blade is inserted in the opening in the cylinder. If so desired, a cotter-pin may be used in place of the lug 22.

I claim:

1. In an electric switch, an insulating base, stationary switch contacts carried thereby, an oscillating carrier, a blade loosely carried thereby and adapted to engage said contacts and a cotter pin passing through said blade for detachably securing it in said carrier.

2. In an electric switch, an insulating cylinder having a transverse passage, a con-

fact blade loosely mounted in said passage and having a projection serving as a stop to limit the endwise movement of the blade in one direction, and means outside of said cylinder for limiting the endwise movement of the blade in the opposite direction.

3. In an electric switch, an insulating

cylinder having a transverse passage, a contact blade in said passage having a projection serving as a stop to limit the movement of the blade in one direction, and a cotter-pin for limiting the movement of the blade in the opposite direction.

BENJAMIN E. GETCHELL.
